United States Patent

Des. 235,328
Patented June 10, 1975

235,328

WHEEL

Donald M. Scraver, Madison Heights, Mich., assignor to
The Budd Company, Troy, Mich.

Filed Sept. 4, 1973, Ser. No. 393,860

Term of patent 7 years

Int. Cl. D12—16

U.S. Cl. D12—211

Fig -1

Fig -2

Fig - 3Fig - 4Fig - 5Fig - 6

FIG. 1 is a front perspective view of a wheel showing my new design;

FIG. 2 is a front elevational view thereof;

FIG. 3 is a sectional view taken substantially along line 3-3 of FIG. 2;

FIG. 4 is a fragmentary sectional view taken substantially along line 4-4 of FIG. 2;

FIG. 5 is a fragmentary sectional view taken substantially along line 5-5 of FIG. 2;

FIG. 6 is a fragmentary sectional view taken substantially along line 6-6 of FIG. 2.

I claim:

The ornamental design for a wheel, substantially as shown.
